UNITED STATES PATENT OFFICE.

BRUNO BRUHN, OF BETHLEHEM, PENNSYLVANIA, ASSIGNOR TO G. POLYSIUS, OF DESSAU, GERMANY, A FIRM.

REGULATING DISCHARGE FROM CONTAINERS.

Application filed April 5, 1927. Serial No. 181,102.

This invention is particularly applicable for use in controlling the discharge of materials which have an abrasive action or which are liable for other reasons to interfere with the proper operation or service of a regulating valve. Merely as an example of one such use, I have in mind the delivery of sand, cement, concrete mixtures or other such granular, plastic or fluid masses or for controlling the discharge of mixtures to rotary furnaces in the manufacture of cement. It is desirable to regulate the rate of discharge, but simple valves when used for this purpose are subject to great wear because of the abrasive character of the material. Consequently, in a very short time, they fail to work properly and must be replaced.

In carrying out my present invention, I provide a plurality of nozzles of different sizes so mounted that any one of them may be brought into operative position. Thus the rate of discharge will depend upon the size of the passage of the particular nozzle which has been brought into operation.

The various nozzles are preferably mounted on a rotatable member and at equal distances from the center of the latter so that they may be brought into and out of position by the mere rotation of the member. In order to facilitate this rotation and the forming of a tight joint between the rotatable member and the vessel outlet, the member is preferably axially movable and is yieldingly held against the outlet.

In the accompanying drawings, I have illustrated one embodiment of my invention, but it will be understood that this may be modified as to details within the scope of the invention as defined in the appended claims.

In these drawings:

Fig. 1 is a central longitudinal section of an apparatus embodying the invention; and Fig. 2 is a plan view of the rotatable member.

The invention is illustrated as applied to a container 10 which may be of any suitable character and adapted to hold any fluid, granular or plastic material, the discharge of which is to be regulated. The bottom of the container has a plate 11 which carries a discharge tube 12 provided with any suit-

able form of shut-off valve 13. At one side of the discharge tube 12, there is provided a bracket 14 serving to support the pivot pin 15 of a rotatably mounted disk 16 which may have a hand wheel or other hand grip portion 16^a to facilitate the rotation thereof. The pin is shown as held against rotation with the disk rotatable on the lower end of the pin.

The disk 15 carries a series of nozzles 17 with passages of different internal diameter, and arranged in an annular row at equal distances from the axis of the pin 15. The center of each nozzle is at the same distance from the center of the pin as is the center of the discharge tube 12. Each nozzle at its upper end has its passage flared to the proper diameter to register with the outlet from the tube 12, and is also preferably provided with means for forming a tight seal with the end of the vessel outlet. Merely as an example, each nozzle is shown as having an annular flange or seat 18 which may fit within a corresponding annular flange or seat on the end of the discharge tube. Thus when the nozzle is moved axially into position, it is held against lateral movement and the disk or member 16 is held against rotation.

To facilitate rotation of the member 16, the pin is preferably made axially movable. The bracket 14 is shown as having lugs for supporting a horizontal pivot pin 19 and mounted on this is a lever arm 20 having a handle 21 at one end and a weight 22 at the other. The pivot pin 19 also has a lever arm 23 extending through a slot in the wall of the bracket 14 and into an aperture in the pivot pin 15. The size of the weight and its distance from the pivot 19 is such that it normally presses the pin 15 upwardly and carries the weight of the latter as well as the weight of the disk 16 and the several nozzles. It also resists any downward thrust on the nozzle due to the movement of the material through the latter. When it is desired to bring a different nozzle into position, the handle 21 is depressed to slightly lower the disk 16 and the latter is then rotated by means of the hand wheel 16^a to bring the proper nozzle into alignment with the discharge tube 12. Upon releasing the handle 21, the weight will lift the disk and nozzles

and hold the selected nozzle in firm engagement with the discharge tube. It will, of course, be obvious that a spring might be used as the full mechanical equivalent of the 5 counter-balancing weight 22.

When it is desired to shut off the flow of material, the valve 13 may be closed, but it will be noted that this valve is always to stand in either closed or wide open position 10 and that the regulating of the rate of discharge is done not by the valve 13, but by the selection of the nozzle of the proper size. The nozzles are preferably made separate from the disk 16 so that they may be replaced, if they become worn. Each may have a flange at its upper end and seating on the upper surface of the disk so that no special attaching or retaining means is necessary.

Having thus described my invention, what I claim as new and desire to secure by Letters Patent is:

1. An apparatus of the character described including a container having a discharge passage, a pivot pin substantially parallel to said passage, a disk rotatably mounted on said pin and having an annular row of nozzles of different diameters, said disk being axially movable and having means for yieldingly pressing it in one direction to hold a nozzle firmly against the end of said passage.

2. An apparatus of the character described, including a container having a discharge passage provided with a shut-off valve, a pivot pin at one side of said member, a lever connected to said pin and having a counter-balancing weight tending to lift said pin, and

a disk rotatably mounted on said pin and having an annular row of nozzles of different diameters, each provided with means for effecting a seating engagement with the end of said discharge passage.

3. In combination, a vessel having an outlet passage provided with a shut-off valve, a bracket at one side of said passage, a longitudinally movable pin mounted in said bracket, a disk rotatably mounted on said pin, an annular row of nozzles of different internal diameters carried by said disk, and each having a flange at its upper end for seating on the disk a seat portion, and a flaring upper end for registry with said discharge passage, a lever pivotally mounted on said bracket and connected to said pin, and a counter-balancing weight connected to said lever for lifting the pin and holding the disk and nozzles in maximum raised position.

4. An apparatus for regulating the discharge of abrasive material, including a discharge passage, a disk having a plurality of nozzles of different internal diameter, said disk being normally stationary, but rotatable to permit any one of said nozzles to be held in registry with said discharge passage, and means for pressing said disk toward said discharge passage to form a tight joint between the discharge passage and the nozzle in registry therewith.

Signed at Bethlehem, in the county of 70 Northampton and State of Pennsylvania, this second day of April, A. D. 1927.

BRUNO BRUHN.
